REMOVABLE CARD TRAY AND PICKER
MECHANISM

Gunnar Nelson, Dayton, Ohio, assignor to The National Cash Register Company, Dayton, Ohio, a corporation of Maryland

Original application April 16, 1937, Serial No. 137,223. Divided and this application April 19, 1940, Serial No. 330,569

2 Claims. (Cl. 271—43)

This invention relates to card supply trays for card perforating mechanisms.

The present application is a division of an application for Letters Patent of the United States, Serial Number 137,223, filed by Gunnar Nelson on April 16, 1937.

In certain types of machines it is desired that the card supply tray be located within a closure and be movable to a more accessible position to replenish the card supply or be removable to make adjustments or repairs.

It is an object of this invention, therefore, to provide a card supply tray which is readily removable to make any necessary adjustments or repairs and is movable to a more accessible position to facilitate the replenishing of the supply of cards.

It is another object of the invention to provide a card picker mechanism attached to the card tray for removal therewith.

It is a further object of the invention to provide novel driving means for the card picker mechanism, which driving means will be readily connectible to and disconnectible from the picker mechanism when the tray is inserted or removed.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In the drawing:

Fig. 1 is a left side elevation of the card supply tray, the picker mechanism, and the driving means for the picker mechanism.

Fig. 2 is a left side elevation of the card supply tray, showing particularly the means for supporting the tray for movement.

Fig. 3 is a plan view of the card supply tray and the associated mechanism.

Fig. 4 is a sectional view of the mechanism for picking the cards out of the supply tray and presenting them to a card feeding mechanism.

Fig. 5 is a bottom view of mechanism associated with the card picker mechanism.

Fig. 6 is a detail view of the means for securing the tray in card feeding position.

General description

When perforating means are used with certain types of machines, it is often desirable that the card supply be locked in a compartment to pre-

vent unauthorized persons from having access thereto. Under these circumstances it is advantageous to use a card supply tray which can readily be moved to a position to receive a fresh supply of cards and also be removable from the compartment so that other trays may be used or to better enable adjustments and repairs to be made to the trays.

A card picker device has been mounted on the tray for removal therewith and enables the throat through which the cards are fed one at a time by the picker device to be kept at a proper opening even though the tray be movable from the position in which the cards are normally fed to the perforating means.

The coupling between a driving means and the picker device is such that the driving means is disconnected from the picker device merely by moving the tray from the position in which cards

20 are fed to the perforating means.

The details of the novel card tray, picker device, and drive for the picker device will now be described.

Detailed description

30 A supply tray 711 (Figs. 1, 2 and 3) for the record cards has a framework, the sides and bottom of which form a receptacle for the blank record cards. The supply tray 711 has flared side plates 712 and a flared top plate 713, which guide the record cards to the blade 714 of a picker device, which also is supported by the frame of the supply tray 711. The cards are advanced through the guide plates 712 and 713 to the picker blade 714 by a spring-pushed pressure plate 715 having fixed thereto a rod 716, opposite ends of which extend through slots in tubular side members 717 and 718 mounted between the plates 712 and brackets secured to the forward end of the tray, and said ends of the rod 716 fit loosely in holes in bearings 719 loose in the tubes 717 and 718. Compressible springs 720, confined between the bearings 719 and screw plugs in the ends of the tubes 717 and 718, urge the pressure plate 715 rearwardly to advance the record cards to the picker blade 714. A bail 721 connected to the pressure plate 715 provides means for pulling said plate forward and holding said plate against the action of the springs 720 when it is desired to insert new cards in the tray 711.

50 The supply tray 711 is accessible through a closure of a compartment shown fully in the parent case, and, when said closure is opened, said tray may be slid forward to a more accessible position for inserting new cards. The tray 711 is slidably mounted by means of horizontal trun-

nions 722 thereon in cooperation with horizontal slots 723 in plates 724 secured to the frames 394 and 395 (Figs. 1, 2, 3, and 6). The tray 711 is locked in feeding position by means of spring-pushed pins 725 in cooperation with corresponding holes in the frames 394 and 395. The pins 725 are connected to respective companion pinch levers 726 pivotally mounted between a plate 727 and the frame of the tray 711. A spring 728 tensioned between extensions of companion levers 726 urges the pins 725, which are slidably mounted in holes in the frame of the tray 711, into their respective locking holes in the frames 394 and 395. The pins 725 are guided into their respective locking holes by notches 729 in the plates 724.

To move the supply tray 711 from feeding position, in which it is shown in Fig. 1, to loading position, it is necessary to compress the companion levers 726 to remove the pins 725 from their respective holes in the frames 394 and 395, whereupon the tray 711 may be moved forward through the closure to loading position, which position is determined by the forward trunnions 722 contacting the forward ends of the slots 723. The tray 711 may be easily removed from the machine for repair or adjustment by moving said tray forward from feeding position to a position where the trunnions 722 are in alignment with an opening in the forward ends of the slots 723 in the plates 724, whereupon said tray may be tilted upward and slid forward until disengaged from the plates 724.

The picker blade 714 (Figs. 1, 3, and 4) is adjustably mounted upon an angular surface on the top of a cross-head 730 mounted for vertical sliding movement upon two guide pins 731 secured in the framework of the tray 711. Protruding from opposite sides of the cross-head 730 are trunnions 732 embraced respectively by the bifurcated forward extensions of levers 733 and 734 pivoted on stationary studs 735 in the frames 394 and 395. Each of the levers 733 and 734 has mounted thereon rollers 736 and 737, which cooperate respectively with the peripheries of companion plate cams 738 and 739 secured on the shaft 566. Counter-clockwise rotation of the shaft 566 and the cams 738 and 739 causes said cams, near the end of a machine operation, to rock the levers 733 and 734 clockwise to shift the cross-head 730 and the picker blade 714 downward. Downward movement of the picker blade picks the first card out of the tray and forces said card downward through a restricted aperture or throat wide enough to admit only one card at a time and formed by a block 740 (Figs. 3, 4, and 5) and an adjustable rail 741, both of which are secured to the framework of the tray 711.

The picker blade 714 carries the card between feed rollers 742 and 743 mounted on shafts 755 and 762, which revolve in opposite directions to feed the record card to a recording mechanism. The details of the recording mechanism and the manner in which the rollers 742 and 743 feed the cards to the recording mechanism form no part of this invention and will not be included in this application. Reference may be had to the parent case for these details.

Sometimes, due to unequal pressure and friction, the cards may become cocked as they are

advanced, by the picker blade 714, through the throat formed by the block 740 (Fig. 4) and the rail 741. In order to overcome this difficulty, spring-pushed fingers 744 and 745 (Figs. 4 and 5) are pivoted on pins supported by a plate 746 secured to the framework of the supply tray 711. The fingers 744 and 745 are urged upward by torsion springs 747 into contact with corresponding projections of the bottom plate 748 of the supply tray 711, and the spring pressure thereon retains the first few cards in the tray in proper alignment with the card picker blade. As the picker blade 714 moves down, downward extensions of a back plate 749 secured to the cross-head 730 engage the fingers 744 and 745 and push said fingers down out of the path of the card being advanced from the supply tray to the feed rolls. The fingers 744 and 745 (Figs. 1, 4, and 5), in cooperation with the extensions of the plate 749, also retain the trunnions 732 in alignment with the bifurcated extensions of the levers 733 and 734 (see also Fig. 3) when the supply tray 711 is shifted forward to loading position or removed from the machine, so that said trunnions 732 will readily engage their corresponding levers when the tray is returned to feeding position.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described, adapted to issue punched record cards, the combination of a supply magazine for the cards, said magazine movable from card feeding position to a more accessible position for inserting new record cards and also removable from the machine; a card picker device to remove the cards from the magazine one at a time, said device mounted on the magazine and removable therewith; a spring pressure means to advance cards into position to be engaged by the picker device; and driving means to operate the picker device, said means engageable by said picker device when the magazine is moved to feeding position.

2. In a combined cash register and card punching machine, adapted to issue punched record cards, the combination of a supply magazine for the cards, said magazine movable from feeding position to a more accessible position for inserting new cards and also removable from the machine; a picker device mounted on the magazine and removable therewith; a spring pressure means, mounted in the magazine, to advance the cards to the picker device; means to reciprocate the picker device to pick the cards out of the magazine one by one; means, including trunnions on the picker device and corresponding notches in the reciprocating means, to connect said picker device to said reciprocating means, when the magazine is in feeding position; and means to retain the trunnions in alignment with the notches when the magazine is out of feeding position.

GUNNAR NELSON.
